Inventor,

Jacob H. Beidler.

By C. M. Alexander
his Atty.

UNITED STATES PATENT OFFICE.

JACOB H. BEIDLER, OF MOUNT PULASKI, ILLINOIS.

CAR-COUPING.

SPECIFICATION forming part of Letters Patent No. 296,114, dated April 1, 1884.

Application filed October 20, 1881. Renewed November 8, 1883. (No model.)

To all whom it may concern:

Be it known that I, JACOB H. BEIDLER, of Mount Pulaski, in the county of Logan, and in the State of Illinois, have invented certain new and useful Improvements in Car-Couplings; and I do hereby declare that the following is a full, clear, and exact description thereof, reference being had to the accompanying drawings, and to the letters of reference marked thereon, 10 making a part of this specification.

This invention relates to railroad-car couplings which are especially designed for freight-cars, but which are also applicable to passenger-coaches; and the nature of my invention 15 consists in the combination of a loosely-hung coupling-pin, a vertically-movable lever from which said pin depends, and a longitudinally-slotted draw-head.

The invention also consists in the combination of a depressing crank-lever and a coupling-link having transverse fulcrum-ridges formed on it at opposite ends of the slot through this link, whereby a person can adjust the link to effect a coupling without going between platforms.

The invention finally consists in the arrangement of spring-buffers on the vertical sides of the draw-head, as will be hereinafter explained.

30 In the annexed drawings, Figure 1 is a perspective view of a draw-head having a coupling-link applied to it. Fig. 2 is a longitudinal section taken in a vertical plane through the center of Fig. 1. Fig. 3 is a horizontal section through the draw-bar and coupling-pin, and a top view of the link.

Similar letters of reference indicate corresponding parts in the three figures.

A designates a draw-head, which may be 40 applied to a car-bed in the usual well-known manner, and which is constructed with a horizontal recess or mouth, B, adapted to receive a coupling-link or slotted bolt, C. This draw-head A is also constructed with oblong slots 45 a a for the purpose of allowing free vertical and swinging motion to a coupling-pin, D.

On each side of the draw-head A is a box, E, which forms a socket, in which is applied a buffer, F, and a spring, b. The buffers F 50 are allowed to receive endwise play, and, be-

ing arranged outside of the mouth B, they are out of the way of the coupling-link in entering said mouth. The coupling-pin D is hung loosely from a hook, c, on the end of a lever, G, which is pivoted on top of the draw-head, so that it is allowed to receive vertical vibration. By means of this lever the pin D can be raised free from the link C to effect an uncoupling. The hook c allows free play to the pin D, and also allows this pin to be detached from the lever, if desired. The lever G may be operated from the top or sides of a car by means of rod or chain connections suitably arranged. The coupling-link C is slightly tapered at its ends, slotted at d to receive the 60 pin D, and constructed with transverse ribs g g at the termini of the slot d. These ribs or ridges g g afford fulcrum for the link C, and allow it to be rocked vertically on the floor of the draw-head by means of a cranked lever, 70 J, shown in Fig. 2.

The ends of lever J may extend to the sides of the car, so that they will be accessible to a train-man without endangering his life or limb. If desired, this cranked lever may be operated 75 from the top of a car by suitable connections.

It will be seen that I have a self-coupling, the link of which can be adjusted by means of lever J, for allowing it to enter the draw-head of a car when cars come together.

Having described my invention, I claim—

1. The combination of a depressing crank-lever, J, a coupling-link and fulcrum-ridges on this link, substantially as described.

2. The combination, in a car-coupling, of a 85 lever, G, of angular form, having a hook on one end, of a coupling-pin hung from said hook, substantially as described.

3. The combination of the sheath E, arranged on the sides of the draw-bar, with the 90 sliding buffers and their springs b, substantially as described.

In testimony that I claim the foregoing I have hereunto set my hand this 11th day of October, 1881.

JACOB H. BEIDLER.
